MACHINE FOR APPLYING ADHESIVES TO
BOTTOM SURFACES

William E. McDonald, Salt Lake City, Utah

Application August 16, 1946, Serial No. 690,879

7 Claims. (Cl. 91—12)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

My invention relates to an adhesive applicator, and more particularly to a device for the application of parallel strips of an adhesive substance to the underside of a box or the like.

It has become customary in the shipment of small boxes, cartons and similar rectangular containers, to assemble them into a composite package by means of gluing them together. In this type of preparation for shipment, loading or unloading of individual packages is unnecessary, and the utilization of mechanical equipment, such as fork-lift trucks, becomes possible. In order to strengthen the composite package, pallets of the same dimension as the top and bottom package of the composite package are glued thereto, whereby the package is further strengthened against shocks, and its handling facilitated. Such a composite package can withstand shocks caused by sudden starts, stops, road bumps, etc., and can be loaded and unloaded in a small fraction of the time needed for handling individual containers.

It has been found in the above-described type of shipment, which has become known as "palletized shipping," that the application of glue to the individual containers by hand is a time-consuming operation. Machines have been proposed to apply dabs of glue to individual containers, which reduces the amount of time spent on the gluing operation; however, the bond between individual packages held together by dabs of glue is not strong. A strong bond can be obtained by coating an entire side of a box with glue; such an operation, while effective, requires a comparatively large amount of glue.

I have found that a firm bond between individual boxes is obtained by applying two parallel strips of glue to a side of a box, preferably at its edges, and assembling and palletizing the boxes into a composite package. I have accordingly devised a machine for applying two parallel strips of adhesive substance such as glue to the flat underside of containers which are fed into the machine manually or by a conveyor.

It is thus an object of the present invention to provide a machine capable of applying parallel strips of glue to the underside of containers moved over the same.

Another object of this invention is an adhesive-applying machine which coats the underside of containers at two parallel edges thereof, and which automatically adjusts itself to the width of containers of various sizes.

A further object of this invention is a simple and sturdy glue applicator which can be easily connected to a conveyor system.

Still another object of this invention is the

2

speeding up and improvement of the assembly of individual containers into composite packages.

These and other objects of my invention are carried out by an adhesive applicator in accordance with my invention, consisting of a plurality of glue applicators and means for automatically adjusting the distance between the applicators to correspond to the width of boxes or similar containers to be glued together, as is more fully shown in the accompanying drawings and the following detailed description thereof.

In the accompanying drawings, which illustrate a preferred embodiment of my invention,

Fig. 1 is a perspective view of an adhesive applicator,

Fig. 2 is a plan view of the same,

Fig. 3 is a side elevation corresponding to Fig. 2.

Fig. 4 is a perspective view of a detail of the adhesive applicator shown in Figs. 1 to 3, and

Fig. 5 is a schematic view of my adhesive applicator in operation.

More particularly, adhesive-applicator stand A consists of two parallel stringers 11 supported by legs 12, and carrying, in sequence, conveyor rollers 13, glue tank 14, glue applicator supporting horizontal shaft 15, and skate wheels W. Shaft 15 slidably carries glue-applicator means, such as a pair of rollers 16, 16', which dip into tank 14 and apply to the underside of a box B. Two parallel ribbons of glue of the same width as the rollers. The rollers, which lie in the same horizontal plane, are resiliently urged toward the center of shaft 15 by a pair of coil springs 17, 17', each carried on shaft 15 and abutting at one end against stringer 11 and at the other end against roller 16 or 16'. Shaft 15 and springs 17, 17' are preferably protected against splashing glue by expandable accordion tubes 18, 18' of rubber or similar material.

A pair of elongated guide arms 19, 19' is hinged to rollers 16, 16' at one end; at their other end the arms are hinged to stringers 11 at 20, 20'. The latter hinges are located forwardly of the glue tank 14 and rollers 16, 16', so that arms 19, 19' will extend obliquely over conveyor rollers 13. In the preferred embodiment of my invention, a hinge 20 or 20' consists of a pin 21 extending downwardly from arm 19 or 19' (see Fig. 4), and a slotted socket 22 mounted on stringer 11 for the reception of pin 21, which may freely rotate in socket 22.

As box B advances over conveyor rollers 13, it engages arms 19, 19' and spreads them apart, overcoming the force exerted by springs 17, 17'. As box B passes over rollers 16, 16', the latter are spread apart to correspond to the exact width of box B, and the glue strips are thus applied to the outer edges of box B.

Conveyor rollers 13 may be power-driven by means of motor 23 which transmits power through

belt 24, or by equivalent means, or they may be gravity-actuated. Glue-applicator rollers 16, 16' are shown without power drive in the embodiment illustrated; they are rotated by frictional engagement of their roughened surfaces with box B which is propelled over rollers 16, 16' by conveyor 13. It will be understood, however, that rollers 16, 16' may likewise be power-driven, if so desired.

After box B has passed glue-applicator rollers 16, 16', it comes to rest on skate wheels W; from there it is removed manually or by conventional mechanical means and stacked to form a composite package suitable for palletized shipment.

While I prefer to use rollers for the application of the adhesive substance to the boxes, other means may be substituted therefor, such as flexible rubber fingers (not shown) on a base slidably supported on shaft 15.

In order to adjust the tension of belt 24, the tail roller 25 is horizontally adjustable on stringers 14 by means of a pair of bolts 26 which bear against the roller shaft resting in horizontal slots 27.

Glue tank 14 may be replenished from a main supply tank (not shown) through pipe 28.

The boxes are fed to the applicator unit by means of conventional conveyors (not shown) linked thereto, or by being placed manually on conveyor rollers 13 and/or belt 24.

My device is simple, and is easy to operate in the manner indicated by its above description. The saving in time and man-hours by its use, as compared with the time and man-hours needed for manual gluing and assembly of individual containers for palletized shipments, amounts to from 33 1/3% to 80%, depending on the type of containers to be assembled.

The adhesive-applicator device, the construction and operation of which I have described in the foregoing specification, may easily be modified to suit the requirements of particular packaging needs by changing dimensions and arrangements of parts of my above-described preferred example, or by substituting equivalents therefor. Such modifications and changes will readily occur to the expert, and are deemed to be within the scope of my invention which I thus intend to limit only by the appended claims.

I claim:

1. Machine for applying an adhesive substance in parallel strips to the bottom surface of a body such as a box, comprising a plurality of applicator means adapted to supply said adhesive substance to said surface, the working surface of said applicator means lying in the same horizontal plane and a support for said applicator means, and means actuatable by said body prior to its contact with said applicator means for varying the distance between said applicator means.

2. Machine for applying an adhesive substance in parallel strips to the bottom surface of a body such as a box, comprising a horizontal shaft, a pair of adhesive substance carrying aligned horizontal rollers slidably on said shaft, resilient means on said shaft for urging said rollers towards the center of said shaft, and means actuated by said body to slide said rollers away from the center of said shaft in divergent directions.

3. Machine for applying an adhesive substance in parallel strips to the bottom surface of a body such as a box, comprising a frame, a horizontal shaft supported on said frame, a pair of adhesive substance applicator means slidably mounted on said shaft and adapted to apply said adhesive sub-

stance to said surface, the working surfaces of said applicator means lying in the same horizontal plane, resilient means urging said applicator means towards the center of said shaft, 5 and a pair of arms hingedly connected to said frame and said applicator means, said arms adapted to be engaged by said body to urge them apart, whereby the distance between said applicator means is adjusted in accordance with the 10 width of said body.

4. Machine for applying an adhesive substance in parallel strips to the bottom surface of a body such as a box, comprising a frame, a horizontal shaft supported by said frame, a pair of adhesive substance carrying aligned horizontal rollers slidably carried by said shaft, and a pair of arms hingedly connected to said frame and said rollers, said arms adapted to be engaged by said body to urge them apart, whereby the distance 15 between said rollers is adjusted in accordance with the width of said body, and means for advancing said body into contact with said arms.

5. Machine for applying an adhesive substance in parallel strips to the bottom surface of a body 25 such as a box, comprising a frame, a horizontal shaft supported by said frame, a pair of adhesive substance carrying aligned horizontal rollers slidably carried by said shaft, and a pair of arms operatively engaging the outer ends of said rollers 30 and extending obliquely outwardly therefrom and adapted to be engaged by said body to urge them apart, whereby the distance between said applicator rollers is adjusted in accordance with the width of said body, and means for advancing 35 said body into contact with said arms and said rollers.

6. Machine for applying an adhesive substance in parallel strips to the lateral edges of the bottom surface of a body such as a box, said 40 machine comprising a frame, a horizontal shaft associated with said frame, a pair of applicator means slidably mounted on said shaft, said applicator means having their working surfaces in the same horizontal plane and being adapted to apply said adhesive substance to the bottom surface of said body, resilient means urging said applicator means toward each other, means hingedly connected to said applicator means and to pivots spaced from said applicator means, said hingedly 45 connected means being adapted to be engaged by said body to urge them apart, whereby the distance between said applicator means is adjusted in accordance with the width of said body, and means for advancing said body into contact with said hingedly connected means and over 50 said applicator means.

7. Machine for applying an adhesive substance in parallel strips to the lateral edges of the bottom surface of a body such as a box, said machine 60 comprising a frame, a horizontal shaft associated with said frame, a pair of applicator means slidably mounted on said shaft, said applicator means having their working surfaces in the same horizontal plane and being adapted to apply said adhesive substance to the bottom surface of said body, resilient means on said shaft urging said applicator means toward each other, means hingedly connected to said applicator means and 65 to pivots spaced from said applicator means, said hingedly connected means being adapted to be engaged by said body to urge them apart, whereby the distance between said applicator means is adjusted in accordance with the width of said body, and means for advancing said body into contact 70

75

with said hingedly connected means and over said
applicator means.
